BAND-PASS AMPLIFIER CIRCUITS

Noël Meyer Rust, Chelmsford, Joseph Douglas Brailsford, London, and Ernest Frederick Goodenough, Springfield, Chelmsford, England, assignors to Radio Corporation of America, a corporation of Delaware

Application April 30, 1941, Serial No. 391,204
In Great Britain October 19, 1939

7 Claims. (Cl. 250—36)

The present invention relates to band pass amplifier circuits and has for its principal object to provide a stable reaction whereby very sharp tuning may be obtained which is practically independent of valve adjustments.

According to the invention a multi-valve stage and an inter-valve coupling stage includes in the cathode leg or lead common to the input and output circuits of each valve a negative feed-back circuit such that the product of the impedance of the feed-back circuit and of the mutual conductance of the valve with which it is associated is considerably greater than unity, the whole arrangement being such as to produce a negative impedance effect which is independent of valve constants.

The invention will be described in connection with the accompanying drawing in which Fig. 1 is a schematic circuit serving to explain the invention; Fig. 2 is an amplifier circuit according to the invention employing common cathode positive feed-back; Fig. 3 are curves showing the gain of the amplifier of Fig. 2 with change in grid bias of the two valves; Figs. 4a to 4c are equivalent circuits which may be utilized in the circuit of Fig. 2 to counteract the dephasing effect of the grid-cathode capacity of the valves; and Fig. 5 shows the application of the present invention to a circuit utilizing a directly heated valve.

Considering Figure 1, it may be shown that the input admittance is given by

$$Y_{IN} = \frac{-g_A g_B Z_{II}}{(1 + g_A Z_I)(1 + g_B Z_{III})}$$

If Z_I and Z_{III} are each made equal to zero, that is if they be absent, there will result the familiar equation

$$Y_{IN} = -g_A g_B Z_{II}$$

If, on the other hand, cathode back coupling be introduced to the extent that the terms $g_A Z_I$ and $g_B Z_{III}$ are each $\gg 1$; the expression becomes

$$Y_{IN} = \frac{-g_A g_B Z_{II}}{g_A g_B Z_I Z_{III}} = \frac{-Z_{II}}{Z_I Z_{III}}, \text{ approximately}$$

Thus by the choice of suitable values for Z_I and Z_{III} in relation to g_A and g_B it is possible to produce a negative admittance at the input terminals of a valve which is dependent upon the impedances Z_I , Z_{II} , and Z_{III} and practically independent of the valve constants g_A and g_B . When Z_I and Z_{III} are circuits of very low Q , it will be seen that the variation of Y_{IN} over a band of frequencies will be practically depend-

ent upon the variation of Z_{II} . If Z_{II} be a series circuit, it can therefore be used to compensate a parallel circuit placed across the input terminals as it will be "reversed":—the reversal effect will however become more and more independent of valve constants as $g_A Z_I$ and $g_B Z_{III}$ are made bigger and bigger compared with unity.

If Z_I , Z_{II} and Z_{III} are each constituted by a parallel resonant circuit having equal Q values, and Z_{II} be made equal to $k Z_I$, Z_{III} and Z_I being equal and both $g_A Z_I$ and $g_B Z_{III}$ being ≥ 1 , then

$$Y_{IN} = \frac{-k Z_I}{(Z_I)^2} = \frac{-k}{Z_I}$$

15 or

$$Z_{IN} = \frac{-Z_I}{k}$$

It will be seen thus that compensation of a parallel tuned circuit connected across the input terminals of the network can be produced by means of three parallel resonant circuits and by the correct choice of values, the effect of valve constants can be eliminated.

25 Cathode back coupling as above described can be applied to a variety of circuits. By correctly relating Z_I , Z_{II} and Z_{III} , and using different types of circuits, a variety of correction effects can be obtained, and the scope of applications is not limited to radio frequencies, e. g. various forms of tone correction arrangements can be devised.

Again the cathode back coupling arrangements can be applied to obtaining stable oscillators in which the frequency is independent to a large extent of valve and supply variations.

It has been found difficult in experimental work to secure stable operation of the crystal "reversed impedance" circuits. It is believed, however, that stabilisation by cathode back coupling should effect improvement. It should be understood that although for convenience of analysis cathode back coupling has been considered, other forms of back coupling may also be employed effectively.

40 Figure 2 illustrates an amplifier circuit with common cathode positive feed back. Each valve is separately stabilised by an impedance in its cathode lead.

45 The gain of such an amplifier is given by the expression

$$G = \frac{g_1^2 Z_I Z_{II}}{1 - g_1^2 Z_I Z_{IV}}$$

50 where g_1 is the effective mutual conductance of

either valve and is equal to $g/(1+gZ_{II})$, assuming $Z_{II}=Z_{III}$.

This may be rewritten as

$$G = g_1 Z_V \frac{g_1}{\frac{1}{Z_I} - g_1^2 Z_{IV}}$$

i. e. Z having added to it in effect a parallel negative impedance equal to

$$-1/g_1^2 Z_{IV}$$

or

$$1/\frac{g^2 Z_{IV}}{(1+gZ_{II})^2}$$

If gZ_{II} be made

$$\gg 1, g_1 \div \frac{g}{gZ_{II}} \div \frac{1}{Z_{II}}$$

The gain then becomes

$$G \div \frac{Z_I Z_V / Z_{II} Z_{III}}{1 - Z_I Z_{IV} / Z_{II} Z_{III}} = \frac{\frac{Z_I}{Z_{II} Z_{III}} \cdot Z_V}{1 - \frac{Z_I}{Z_{II} Z_{III}} \cdot Z_{IV}}$$

and thus approaches a maximum value as g is increased. This is clearly shown by the curves of Figure 3 which show gain in decibels against grid bias of the two valves.

When the amplifier was set to oscillate by slightly increasing Z_{IV} considerable improvement in the stability of frequency of oscillation with change of the H. T. voltage was noticeable, when compared with an unstabilized oscillator. In this amplifier, the cathode circuits Z_{II} , Z_{III} , Z_{IV} , were of very low Q , but were tuned to a somewhat lower frequency than that of the circuit Z_I , which was 455 kc. This was to counteract the dephasing effect of the grid-cathode capacity of the valve.

The grid cathode capacity may be tuned out by coupling the coils tuning the grid and cathode circuits. This may be accomplished in various ways, such as shown in Figs. 4a, 4b and 4c in which the coils only are shown coupled by the grid-cathode capacity C , and mutual inductance M . Coil L_1 of Fig. 4a may correspond for example to the coil of Z_1 in Fig. 2 and coil L_2 of Fig. 4a may correspond for example to the coil of Z_{III} in Fig. 2.

These coils L_1 and L_2 are coupled by a positive mutual inductance M as in Figs. 4a and 4b, and in Fig. 4c the coupling is adjusted so that L_A tunes with C at the working frequency, the net coupling between L_B and L_C then being zero.

The correct coupling is easily found in the case of Fig. 4a by tuning the coils L_1 and L_2 with condensers, and adjusting the coupling until the double hump response measured at the grid of the valve becomes a single hump, i. e. until the voltage, measured by a separate valve voltmeter, becomes a maximum, showing that the two tuned circuits are effectively uncoupled. The valve concerned should be rendered inoperative to avoid complication due to feed back effects.

The anode-cathode capacity may be similarly tuned out by coupling inductances in the anode lead and cathode lead.

It may also be shown that compensation for the effects of the grid/cathode capacity so far as feed back from the cathode circuit is concerned, may be obtained by this means. This may be useful in cases, for example, where feed back

from cathode to grid is via a four-terminal network, such as a tapered line.

The use of a cathode stabilising impedance has been found to render a single valve reaction circuit stable and reliable, especially if a high g value be used. Greater stability of oscillation with variation of H. T. voltage than for the two-valve arrangement was also obtained with this circuit, when made to oscillate.

10 In a directly heated valve, the use of a cathode circuit is not permissible for the provision of negative feed-back for stabilising purposes. The circuit described below has been devised to overcome this difficulty when used in conjunction with a positive feed back arrangement.

15 Figure 5 shows the circuit of a reacting detector valve, where Z_I is the ordinary tuned circuit to which reaction is applied by a coupling coil from the anode. The earth end of this coil is connected to the junction of the impedances

20 Z_I and Z'_{II} where Z'_{II} takes the place of the cathode circuit hitherto considered. The current in the anode circuit is in antiphase with that in the grid circuit, so that the voltage developed across Z'_{II} will be in antiphase to that developed across

25 $Z_I + Z'_{II}$ by the input current. This negative feed back tends to effect the positive feed-back provided to Z_I by the coupling coil, the coupling of which must therefore be tightened. As in the other circuits considered, any change in the valve 30 that changes the positive feed-back, i. e. the equivalent negative impedance shunting Z_I , also changes the negative feed-back by the same amount and the net change is thereby reduced.

35 The coils tuning Z_I and Z'_{II} are coupled by a positive mutual inductance to tune out stray capacitances shunting them. Z'_{II} , moreover, may be of low Q .

What we claim is:

40 1. A multi-valve stage comprising a pair of valves, an inter-valve coupling impedance therebetween, and an impedance in the common part of the output and input circuits of each valve for producing negative feed-back from the output to the input of each valve, the value of each cathode impedance being such that the product of the impedance and the mutual conductance of the valve with which it is associated is considerably greater than unity, the arrangement being such as to produce a negative admittance effect at the input of the stage which is independent of valve constants.

45 2. A multi-valve stage as claimed in claim 1 wherein the cathode returns of said valves have a common portion in which there is included an impedance network for providing positive feed back from the output to the input of the stage.

50 3. A circuit arrangement in accordance with claim 1 wherein the cathode returns of said valves have a common portion in which there is included an impedance network for providing positive feed-back from the output to the input of the stage, the value of the impedance of the said positive feed back network being such as to cause 55 the said circuit arrangement to oscillate.

60 4. A circuit arrangement as claimed in claim 1 wherein the inter-valve coupling impedance comprises a parallel tuned circuit, the negative feed-back impedance in the common part of the output and input circuits of second valve also comprising a parallel tuned circuit, and wherein the grid cathode capacity of said valve is tuned out 65 by coupling the coils of the two said tuned circuits.

5. A circuit arrangement as claimed in claim 1 wherein the cathode returns of said valves have a common portion in which there is included an impedance network for providing positive feed-back from the output to the input of the stage, the negative feed-back impedances and the positive feed-back network are constituted by circuits of low Q value and are tuned to a lower frequency than the inter-valve coupling impedance.

6. A multi-valve stage comprising a first valve A having in the common part of the output and input circuits thereof a negative feed-back circuit having an impedance value Z_I and in the output circuit thereof an impedance value Z_{II} , and a second valve B having in the common part of the output and input circuits thereof a negative feed-back circuit having an impedance value Z_{III} , and wherein $g_A Z_I$ and $g_B Z_{III}$ are each $\gg 1$ 20

whereby the input admittance Y_{IN} of the first valve is equal to

$$\frac{-g_A g_B Z_{II}}{g_A g_B Z_I Z_{II}} \cdot \frac{-Z_{II}}{Z_I Z_{III}}$$

5 and wherein Z_I and Z_{III} in relation to g_A , the mutual conductance of valve A, and g_B , the mutual conductance of valve B, are so chosen as to produce a negative admittance at the input terminals of valve A which is dependent upon the impedances Z_I , Z_{II} , and Z_{III} and practically independent of the valve constants g_A and g_B .

10 15 7. A circuit arrangement as claimed in claim 6 wherein Z_I and Z_{III} are circuits of very low Q whereby the variation of Y_{IN} over a band of frequencies will be practically dependent upon the variation of Z_{III} .
